W. E. WILLIAMS.
STEEL END FOR CARS.
APPLICATION FILED FEB. 19, 1914.

1,129,769.

Patented Feb. 23, 1915.

UNITED STATES PATENT OFFICE.

WILLIAM ERASTUS WILLIAMS, OF CHICAGO, ILLINOIS.

STEEL END FOR CARS.

1,129,769.

Specification of Letters Patent. Patented Feb. 23, 1915.

Application filed February 19, 1914. Serial No. 819,683.

To all whom it may concern:

Be it known that I, WILLIAM ERASTUS WILLIAMS, a citizen of the United States, residing at Chicago, in the county of Cook and State of Illinois, have invented a new and useful Improvement in Steel Ends for Cars, of which the following is a specification.

Railway cars receive severe shocks and impacts, by the sudden stopping of the cars and in coupling them in switching and this shock often shifts the loads on the inside of the cars and drives them backward into the ends and often times punctures, breaks and destroys the ends of the cars.

The object of my invention is to produce a light, strong and cheap end that will withstand the shocks of this service and at the same time be most serviceable as a car for normal car services.

References will be had to the accompanying drawings, in which:

Figure 1 is an end view of a box car embodying my end. Fig. 2 is an end sectional elevation of my end with a small portion of it showing from the outside the connection of the end to the corner post. Fig. 3 is a horizontal section showing a corner portion of a car in which the corner post and sheathing are of wood. Fig. 4 is a view similar to Fig. 3, showing my end used without the flanges turned to embrace the outside of the corner post, and it also shows in plan the bottom flange of my end. Figs. 5, 6 and 7 show the arrangements of my end when the same is used in connection with a steel angle corner post and inside wood sheathed car, Fig. 5 being analogous to Figs. 3, 4. Figs. 8 and 9 are enlarged details of the ribs of my end. Figs. 10 and 11 are enlarged sectional views corresponding to parts of Fig. 2.

In drawing 2 indicates the steel sheet of my end. In this sheet I form ribs 3 by putting sharp folds in the sheets which are bent up and form the ribs, and I extend these ribs across the end of the car at intervals of sufficient distance apart to give the required stiffness to the sheet.

In the construction shown in Fig. 3, I bend the end of the sheet cross-wise of the flanges around into the angle shown by 4, Fig. 3. 5, indicates the rib 3 at the curve of the bend around the corner. Bolts 6 and 7 pass through the sheet and the corner post and securely fasten the end to the corner post.

In Fig. 4 the steel end sheets do not run around the corner post forming the flange 4, but terminate at 8 and the bolts 6 fasten the end sheets to the corner post. 60

The present practice in car construction is turning toward a steel frame for the box car, having a wooden sheathing on the inside and when such a car is used with my steel end the corner post will appear as I 65 prefer to make them in accordance with Figs. 5, 6 and 7, wherein 9 indicates a steel angle for the corner post; slots 10 are cut through one flange of the angle at locations registering with the position of the ribs 3 70 of the end sheets and these ribs project through the slots 10, as is shown by the figure. This does not weaken the corner post for the reason that the steel end sheets themselves, are bolted securely by the bolts 6 75 through the flanges of the angle and make up for any loss occasioned by the slots 10.

In making my steel end I prefer to make it out of metal $\frac{1}{8}$ or $\frac{1}{6}$ of an inch thick and the ribs 3 so stiffen it that the results 80 obtained will be even greater using $\frac{1}{8}$ of an inch sheet for the steel end than would be the case with $\frac{1}{4}$ of an inch sheet as sometimes heretofore used.

On the inside of my steel end I prefer to 85 line it with wood, and this wood may be any thickness desirable from $\frac{1}{8}$ of an inch up to $\frac{1}{4}$ of an inch, as a thick wood sheathing is not necessary since my metal sheets provide almost a complete smooth plate surface for 90 the wooden sheathing to lie in contact with, and thus almost no breaking strain can go on the sheathing as the metal will bear all of the strain that may be occasioned by the impact of any load on the inside of the car. 95 In order to facilitate the fastening of this sheathing on the inside of my steel end I make the ribs 11, 12 and 13, leaving a cavity in which I place the wood strips 14, 15 and 16 which are bolted in to this cavity by bolts 100 17 and the sheathing is nailed on to these strips.

I prefer to make my end using two pieces of steel running cross-wise of the car and I join the two sheets at the rib 12, making the top sheet overlap the rib on the lower sheet in such manner that water from rain may not trickle down on the inside of the sheet but will drop off on the outside.

The lower margin of the sheet 2 is bent 110 inward forming a flange 19 which rests upon and is bolted to the sill 18.

Steel ends for cars have been made out of corrugated sheets of various different kinds. When the horizontal corrugations are used which gives a cross section analogous to the 5 surface of ordinary corrugated iron or sheathing and it is then desired to line the end with wooden sheathing, it is a difficult and expensive task to apply a wooden sheathing to such an end that will not leave voids 10 between the corrugations of the end and the wooden sheathing, while voids are seriously objectionable because they gather dirt, grain and any loose material with which the car may be loaded, and then on the next loading 15 of the car this material may be shaken out by the vibration of the car and injure the new load. With my steel end and wooden sheathing, no voids are produced that will remain open or need to be filled, and hence 20 this feature is a great desideratum. Further with a steel end made of corrugated material and sheathed with wood which rests against the summits of the corrugations as is ordinarily the case, as heretofore used, 25 this wooden sheathing is likely to be punctured between the corrugations by shifting loads that will go in contact with the sheathing in small spots like the corners and ends of bars of iron or small ends of sticks 30 of timber and this wooden sheathing with that class of steel end is objectionable, but with my end these objections are overcome.

For certain kinds of loading in a car, it is desirable that the steel ends should be 35 sheathed and no other form for steel ends heretofore used will permit the steel to be used in connection with a wooden sheathing that will not cost more money for the same service than with my steel end. This feature 40 is a great point in favor of my invention.

It is desirable to have a wooden lining to a car from the standpoint of insulation in temperature and it aids often times in 45 curing the load in the car in a fixed position by nailing cleats or braces to the inside of the car.

My end gives all the advantages obtained by any wooden end and all advantages obtained by any steel end and yet it can be so cheaply made that it is a competitor in cost 50 for any form of end construction of a car.

One of the features which permit my end to be made cheaply is the fact that in making ribs 3, the metal may be bent when it is cold and cold operations are cheaper than hot operations. Heretofore all other steel ends yet used have been formed by hot operations.

60 What I claim is:

1. In a car end, the combination with a metal sheet of uniform thickness folded on parallel lines to form an internally plane

structure having spaced horizontal ribs of a thickness double that of the sheet, of wood 65 sheathing transverse with respect to the ribs and secured to the plane face of the sheet.

2. In a car end, the combination with a uniformly thin metal sheet folded at intervals along parallel lines to form an internally plane member having a series of external, tightly closed ribs and intermediate internally open ribs, of wood strips, fixed in the internally open ribs, wood 75 sheathing fixed to the strips, and means for securing the structure to the body of a car.

3. In a car end, the combination with a metal sheet folding along parallel lines to form a series of external horizontal ribs, of a second sheet above the first, similarly folded and having its marginal rib overlapping externally and interlocking with the marginal rib of the first sheet, means for binding together the overlapping portions 85 of the two sheets, and means for securing the sheets to the body of the car.

4. A steel end for a car formed of a flat sheet having ribs formed in the body thereof in a manner that leaves a substantially 90 flat surface on one side of the sheet, said ribs extending cross-wise of the end of the car, with a corner post made of metal and having a flange that embraces the body of the end sheet between the ribs thereof. 95

5. In a car end, the combination with a metal sheet folded along parallel lines to form a series of external parallel ribs of a thickness double that of the sheet and an upper marginal internally open rib, of a 100 second sheet similarly folded and having a lower marginal open rib overlapping and interlocking the open rib of the first sheet, a wood strip fitting the open rib of the lower sheet, bolts passing through said strip and the overlapping portions of the two sheets, and sheathing transverse with respect to the strips and secured thereto. 105

6. A car end of sheet metal folded along parallel lines to form an internally plane 110 member having a series of tightly closed external ribs and a series of intermediate internally open ribs, each of uniform width from side to side of the sheet, combined with wood strips secured in the open ribs, 115 and wood sheathing transverse with respect to the strips, secured thereto, and covering the plane non-ribbed face of the sheet.

Signed at Chicago in the county of Cook in the State of Illinois this 17th day of February, 1914. 120

WILLIAM ERASTUS WILLIAMS.
